UNITED STATES PATENT OFFICE.

WILLIAM H. BOOTH, OF KINCARDINE, ONTARIO, CANADA.

GAME.

Application filed October 28, 1924. Serial No. 746,329.

The invention relates to games, and has as its object the provision of a game of skill, utilizing a board and a projector, and which may be made to simulate baseball, 5 cricket, or other types of games.

An object of the invention is the provision of a game utilizing the rules of baseball or cricket, which may be played by a number of players.

10 A further object of the invention is the provision of a game, lacking the elements of chance, in which players may develop great skill in the manipulation of a ball.

15 A further object of the invention is the provision of a board which may be utilized in playing a game.

20 A further object of the invention is the provision of a projector by which balls may be impelled over a surface in a large variety of curves or in a straight path.

A further object of the invention is the provision of an attachment to a board to simulate a cricket wicket.

25 A further object of the invention is the provision of means to represent a batter running bases which may introduce the time element of the retrieving of a batted ball.

30 A further object of the invention is the provision of a board having means to cause a ball to fly into the air when batted over the surface of the board.

35 Further objects of the invention will appear from the following description when read in connection with the accompanying drawings, in which—

Fig. 1 is a plan view of a game board;

Fig. 2 is a side elevation of the same;

40 Fig. 3 is a central vertical section of the board;

Fig. 4 is a side elevation;

Fig. 5 is a plan view of a form of projector;

45 Figs. 6 and 7 are perspective views of forms of bats;

Fig. 8 is a detailed vertical section of a board showing a wicket applied thereto; and

50 Fig. 9 is a perspective view of the wicket attachment separated from the board.

As shown, the board comprises a flat base member 10, desirably made of beaver board or of wood, and which may, if desired, be covered with a fabric, not shown, such as 55 felt.

To prevent the ball from rolling off from the board, there is shown a fence 11, surrounding the board on three sides.

To cause a ball batted along the surface of the board 10 to fly into the air, the end 60 of the board, representing the boundary of the infield, is shown as edged with a sloping deflector board 12.

Desirable dimensions for the board, when used to simulate a base ball game or a 65 cricket game, are about four feet from the pitcher's box, indicated at 13, to the home plate, indicated at 14, and a desirable length for the deflector board 12 is substantially four feet, with a width thereof of substantially 70 four inches.

To introduce the time element of a running batsman, there is shown an inclined plane 15, adapted at its extremity 16 to deliver to a second inclined plane 17. The 75 inclined planes are shown as secured to the fence 11 of the board. The inclined planes 15 and 17 are grooved to enable a ball, such as a steel ball-bearing ball of suitable size, to roll as on a track. 80

To hold the ball in position to be released, without being given an initial push or impulse, and to thus travel freely by gravity upon the inclined plane, there is shown a member 18 pivoted at 19, between the 85 uprights 20, between which uprights one end each of the inclined planes 15 and 17 is secured. The member 18 is provided with an opening of a size to receive the ball 21, and when the batsman strikes the ball 90 pitched to him across the home plate 14, he immediately depresses the projecting end of the member 18, thereby causing the ball holding end thereof to rise and to release the ball 21, but to give the same no 95 impulse to assist gravity in causing it to roll.

An upright or uprights 22 are provided at the central points of the inclines 15 and 17 to indicate first and third bases respectively, second base being indicated by the end of the incline 15, and home base by the lower end of the incline 17. 100

To propel a ball across the board to simulate a pitched ball, an implement is 105 shown in Figures 4 and 5, comprising a wire frame, which may be formed from a single length of wire, and presents fingers 23, 24, and 25. The outer members of the fingers 23 and 25 are shown as turned inwardly at 110

26 and 27, and upwardly in close relation to each other, and as having a handle of suitable material, as wood, 28, slipped over them. The middle finger 24 is shown with a covering 29, preferably of rubber, so as to secure a grip upon the ball in excess of the grip of a finger 23 or 25.

The device is used by placing the ball upon the board, upon the pitcher's plate 13, and pressing downwardly upon the projector with a slight backward movement thereof to suddenly shoot the ball out from under the fingers. The difference in friction between the finger 24 and that of one of the other fingers will result in a spinning movement of the ball at an angle to the surface of the board, thereby causing a curved path of the ball. A desirable form of ball to use is a hollow shell of celluloid, and those known to the trade as ping-pong balls are quite suitable.

Some of the forms and directions which the path of the ball may be caused to take, are indicated by dotted lines in Fig. 1. A swift straight ball may be delivered by so manipulating the projector as to give a straight backward spin to the ball, which is overcome by the forward impulsion of sufficient force to prevent the grip of the ball upon the surface from deflecting its course, or a slow uniform curve, such as indicated at 30. A sharp break such as shown at 31 or 32, or a slow break such as shown at 33, may be had.

The illustrated forms of the curve which the ball may be caused to take, are only a very few of a large number of most illusive curves which may be delivered, and a skilled player may cause the curves to come across the plate very unexpectedly or when appearing to be about to cross the plate the ball may be caused to evade the same.

To bat the thus delivered ball, one of the forms of bats shown in Figures 6 or 7 or many other shapes or types may be utilized. The bat shown in Fig. 6, at 34, is a usual baseball bat, in miniature, and that shown at 35 in Fig. 7 is more in the form of a paddle, and is adapted for inexperienced players.

The bat is to be held by the thumb and first two fingers, in the same manner as a pencil or pen, but vertically, and to be given a quick forward motion by the impulse of the second finger. By this action, the bat may be caused to contact with the ball closely adjacent the fence 11, at the home plate 14.

To adopt the board for a simulation of the game of cricket, the wicket apparatus shown in Figs. 8 and 9 may be utilized by simply clipping the same over the fence back of the home plate 14. As shown in these figures, the wicket device comprises a bar 36 carried by rearwardly projecting bars 37-38, provided with clips 39-40, adapted to engage the upper edge of the fence. Pivoted

for free motion upon the bar 37 are shown the vertical stumps 41, and loosely laid upon their upper ends the bail member 42.

When a ball, such as is shown in dotted lines at 43, projected by the bowler, by means of a device of the nature shown in Fig. 4, strikes the lower end of any one of the stumps 41, the stump or stumps will be thrown into the dotted line position of Fig. 8, and the bail will fall in the same manner as in field cricket.

It will be understood that the form of projector shown in Figs. 4 and 5 is illustrative only. The essential feature of the projector is that it shall have a lower surface, represented in the form shown by a common plane in which the fingers 23, 24, and 25 lie, having a portion providing a greater grip upon the ball than another portion so that the result of a snapping action, by allowing the ball to slip from under the projector, shall be a spin, to vary the path which the ball takes.

A simple paddle with a strip of adherent material, such as rubber, would perform the function, and has been tried with good results. However, the form shown is the best form at present known, and in addition to the difference between the frictional effect of the bare wire and the rubber-covered finger, this form acts by allowing the ends of the fingers to spring apart about the back, rounded surface of the ball, and to thus not only act upon the ball by a straight forward impulse, but by the spring action of the fingers coming together about the curved backward portion of the ball. During this action the frictional difference between the metal and rubber surfaces has an added effect over what is secured by a plain surface.

The juncture between the wire forming the fingers 23 and 25, with the center wire 24, is carried a substantial distance to the rear of the handle 28 as at 44-45. In this manner, the spring action laterally between the fingers, is enhanced. An additional number of fingers could be utilized, providing, if desired, two rubber-covered fingers for projection of a straight ball with backward spin.

Many other games may be devised, utilizing the method of projection of a ball provided by the invention, and many minor changes may be made in the physical embodiment of the invention, without departing from the spirit thereof.

I claim:

1. A playing board comprising a playing surface in the shape of a trapezoid having fence-like closures for its narrow parallel side and for its diverging sides, a deflector board bounding its longer parallel side, meeting said surface at an angle whereby to cause an article projecting along said surface to leave said surface upon engagement

with said deflector board and to travel freely through the air.

2. A playing board comprising a playing surface bounded by a closure, said surface having a pitcher's position and a batter's position, a portion of said closure comprising a deflector meeting the surface at an angle greater than 90 degrees whereby to deflect an article projected along the surface to cause the article to leave the board and to travel freely through the air, said deflector partially surrounding the pitcher's position rearwardly and laterally thereof.
3. A playing board comprising a playing surface having a batsman's position indicated thereon, a deflector board bounding the playing surface at its end opposite the batsman's position, and meeting said surface in the arc of a circle having its center substantially at the batsman's position, said deflector board inclined upwardly from the surface, whereby to cause an article projected along said surface to leave the surface and travel freely through the air.
4. A playing board comprising a playing surface, a pair of vertically arranged oppositely inclined tracks carried by said board adjacent said surface, means to mark the center of said tracks to represent the bases

of a base runner, means at a lower end of the upper track to deliver the traveling member to the lower track and to indicate a second base, means to stop a traveling member at the end of the lower track to represent a home base, and means to release a traveling member at the upper end of the upper track without initial propulsive impulse.

5. A playing board comprising a playing surface, a fence carried by said surface, a wicket attachment comprising a horizontal bar mounted upon said fence and spaced therefrom, stumps pivotally mounted upon said bar for free oscillation, and a bail loosely carried by the upper ends of said stumps.

6. A playing board comprising a playing surface, a fence bounding a portion of said surface, a wicket attachment comprising clips taking over the edge of said fence, horizontal members carried by said clips, a transverse horizontal bar carried by said horizontal members in spaced relation to said fence, stumps pivotally mounted upon said bar intermediate their length for free oscillation thereof, and a bail loosely laid upon the upper end of said stumps.

WILLIAM H. BOOTH.
